UNITED STATES PATENT OFFICE.

JOHN H. STEWART, OF JAMAICA, NEW YORK.

DESIGN FOR A PUSH-PLATE FOR PANIC-DOORS.

48,134.

Specification for Design.

Patented Nov. 9, 1915.

Application filed May 1, 1915. Serial No. 25,288. Term of patent 3½ years.

To all whom it may concern:

Be it known that I, JOHN H. STEWART, a subject of the King of England, residing at Jamaica, in the county of Queens and State of New York, have invented a new and original and ornamental Design for Push-Plates for Panic-Doors, of which the following is a specification, reference being had to the accompanying drawing, forming part thereof.

Figure 1 is a perspective view of a push plate for panic doors showing my new design, and Fig. 2 is a sectional view of the same, showing more clearly the configuration of the front and back of the plate.

I claim:

The ornamental design for a push plate for panic doors, as shown.

JOHN H. STEWART.
